Atty.

UNITED STATES PATENT OFFICE

WILLIAM T. CRAVEN, OF PHILADELPHIA, PENNSYLVANIA

HANGER FOR BRUSHES, BROOMS, ETC.

Application filed June 26, 1928. Serial No. 288,523.

My invention relates to new and useful improvements in a hanger for brushes, brooms, etc., and has for one of its objects to provide an exceedingly simple and effective device of this character which may be readily and quickly placed upon or removed from the handle of a brush or the like and when thereon may be used for hanging the article to which it is attached on a nail or similar support.

Another object of the invention is to provide a hanger of the class mentioned including a split tubular barrel of rubber having oppositely disposed sockets, each ninety degrees from the split portion for the reception of the ends of a bail.

A further object of the invention is to provide a hanger for brushes and the like comprising a barrel of flexible material slipped longitudinally at one location and provided with protuberances, each ninety degrees from the split, said protuberances having sockets for the reception of the ends of a bail whereby the object to which the hanger attached may be suspended from a support.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of this application, in which:

Fig. 1 is an isometric view of a brush showing my hanger mounted thereon.

Fig. 2 is an elevation of the bail.

Fig. 3 is an end view of the barrel with a portion broken away and shown in section to illustrate a detail of construction.

Fig. 4 is a side elevation of the barrel partly in section taken on the line 4—4 of Fig. 3.

In carrying out my invention as herein embodied, 5 represents a barrel or tube of suitable flexible material, such as rubber split longitudinally at one location, as indicated at 6 whereby said barrel or tube may be opened and placed sidewise and over the handle 7

of a brush 8 or the like, or said tube or barrel may be slipped endwise over the brush handle and then slid longitudinally until the desired position is obtained.

By opening the tubular barrel slightly, it can be moved along the handle easily because of the reduced contact surfaces.

The barrel being slipped also makes it possible to use it on different sized handles, for instance, if the barrel is made to accommodate a $\frac{1}{8}$ inch handle, it may also be used on those of larger dimensions.

By making the tube or barrel of rubber, there will be sufficient friction between its inner surface and the outer surface of the handle to prevent slipping unless considerable outside pressure is brought to bear thereon the barrel while having a straight opening therethrough has its exterior shaped in the form of a barrel in order that the center portion thereof may be thicker while it tapers to a comparatively thin edge at each end. This construction causes the central portion of the device to grip the broom-handle with greater pressure than the ends thereof and facilitates the insertion of the broom-handle therein since when the handle is being forced upward into the device the thin lower edges thereof will more readily flex outward.

On the outside of the barrel, in diametrical- 80 ly opposite locations, are formed a pair of protuberances 9 preferably midway the ends of the barrel and ninety degrees from the split 6, and in these protuberances, are formed the sockets 10 for the reception of the in-turned ends or trunnions 11 of the bail 12 which is preferably formed of wire.

The wire bail is sufficiently resilient to normally force the adjacent edges of the split together, thus assisting in holding the barrel firmly in its adjusted location on the handle.

In practice, the hanger may be readily and quickly placed upon the handle of any article and just as readily removed therefrom so that it can be used on different articles or replaced on the same article after the user has finished with said article.

When the hanger is on the handle of the article, said article may then be suspended from a nail or other support by placing the 100

bail 12 over such support and if so suspended, the brush bristles will be kept in very good condition.

Of course I do not wish to be limited to the exact details of construction as herein shown, as these may be varied within the limits of the appended claims without departing from the spirit of my invention.

Having thus fully described my invention, what I claim as new and useful is:—

10 1. A device of the kind described comprising a rubber barrel open from end to end and split along a single line longitudinally to permit its application to or removal from the handle of an article, protuberances formed on the exterior of said barrel at diametrically opposite points and ninety degrees on each side of the split, said protuberances having sockets therein and a resilient bail, the ends 20 of which engage said sockets and assist in holding the barrel on the article handle.

25 2. A device of the character described, comprising a split rubber ring, the body of which is thicker at the central portion than at the ends thereof to give a firm grip upon a broom-handle while permitting the ready insertion of said handle into the ring, two bosses formed with the body, said bosses having recesses therein and a wire bail, the ends of 30 which are adapted to enter said recesses.

In testimony whereof, I have hereunto affixed my signature.

WILLIAM T. CRAVEN.
